APPARATUS FOR CASTING BRAKE SHOES
CENTRIFUGALLY

William B. Weaver, deceased, late of Birmingham, Ala., by Carrie J. Weaver, executrix, Birmingham, Ala.

Application April 4, 1930, Serial No. 441,481

7 Claims. (Cl. 22—65)

The invention relates to a process and apparatus for making brake shoes, and more particularly to a method and apparatus for casting brake shoes centrifugally.

The objects of the invention include the provision of a relatively simple, dependable, highly efficient and convenient process and apparatus of the type above indicated.

Various further and more specific objects, features and advantages will clearly appear from the detailed description given below taken in connection with the accompanying drawings, which form a part of this specification and illustrate by way of example one embodiment which the invention may take.

In the drawings

Figure 1 is an elevation of a complete system according to the invention;

Figure 2 is a vertical section through one of the casting machine units;

Figure 3 is a section on the line 3—3 of Figure 2;

Figure 4 is a section on the line 4—4 of Figure 2;

Figure 5 is a section on the line 5—5 of Figure 2;

Figure 6 is a view, partly in section, showing the mold separated;

Figures 7 and 8 are sections taken on the lines 7—7 and 8—8 of Figure 3;

Figure 9 is a section on the line 9—9 of Figure 5;

Figure 10 is a section on the line 10—10 of Figure 9;

Figure 11 illustrates the complete ring of brake shoes when cast;

Figure 12 represents a section of the flat insert forming part of the brake shoe;

Figure 13 is a detail showing the brake shoe pin holder in developed form;

Figure 14 is a perspective illustrating a section of the insert with a pin holder assembled thereto;

Figure 15 is a detail of the pouring pipe;

Figure 16 is a section on the line 16—16 of Figure 2; and

Figure 17 is a perspective of a completed brake shoe.

In the following description and in the claims parts will be identified by specific names for convenience, but they are intended to be as generic in their application to similar parts as the art will permit.

Like reference characters denote like parts in the several figures of the drawings.

Referring now to the drawings, and more par-

ticularly to Figures 11, 12, 13, 14, and 17, one type of brake shoe is shown for the purposes of illustration, but it will be appreciated that other types of brake shoes may be made according to the teachings of the invention. The brake shoe 5 comprises an insert, indicated by 21, having a central portion 25 with slots 26, and opposed legs 24. Secured to the insert is a pin holder 22 having lugs 21, which fit in the slots 26, and are bent over thereunder. The bending of the pin holder 10 22 forms a hole 28, and further holes 29 are provided in the sides of the pin holder for assisting in attachment to the rigging of the braking mechanism on the railroad freight car, or other apparatus on which the shoe is used.

15

The metal insert 21 with the assembled pin holder 22 is cast within a body of metal 20, which forms the body of the brake shoe. The brake shoe has T-shaped lugs 23 on the ends thereof to cooperate with the brake rigging of the car 20 on which the brake shoe is used.

Having described the construction of one particular type of brake shoe, the machine for casting the brake shoe will now be described. Referring now to Figure 1, the machine as illustrated comprises two casting units 31 operated by a motor 30 therebetween. Pouring mechanisms one for each unit, indicated by 32, are provided for pouring the cast iron. A solenoid brake 33 may be provided on the motor shaft for stopping the rotation of the casting machines at the desired positions. The entire apparatus may be mounted upon a suitable foundation or base 34.

Referring now to Figure 2, each casting machine unit comprises a base 36 having a wall 37 secured thereto, which in turn supports a bearing 38 in which is journaled a hub 40, which is secured to the drive shaft of motor 30 through a suitable coupling. A suitable gland and packing, indicated by 39, is provided for making a 40 water-tight joint. Also secured to the base 36 is a bearing 41, which supports a mold carrier 45. A further gland and packing, indicated by 42, is provided for forming a water seal at this point.

The centrifugal mold proper comprises a mold 45 carrier 45, which is bolted to the hub 40. It will be understood that the mold carrier 45 and hub 40 are journaled in the bearings 38 and 41, and that water is introduced into the space indicated by 35 therebetween. Cooling water may be introduced through pipe 200, and may leave through pipe 201. If desired, the bearing 38 may be arranged to take substantially all of the weight of the rotary mold.

Bolted to the mold carrier 45 is an axially fixed 55

mold section 46. Also fitting within the mold carrier 45 is a removable mold section 47, which is secured to the arms 63.

An axially moving carriage 48 rests upon suitable tracks 49 (Figure 4), and has a rack 53 secured to the underside thereof. A drive shaft 51 is suitably journaled on a base 50, and carries a spur gear 52 meshing the rack 53. A spur gear 54 is also mounted on shaft 51, which is 10 driven by motor 55 for moving the carriage 48 axially.

Carriage 48 carries a support 60, which carries bearings 61, in which is journaled the hub 62, which, in turn, carries the arms 63. Thus it will 15 be seen that by moving the carriage 48 to the right in Figure 2, the mold section 47 may be separated from the mold section 46.

It will be understood that the mold sections 46 and 47 are suitably shaped to mold the ring 20 of brake shoes indicated in Figure 11. As shown in Figure 3, the mold has a plurality of recesses 66 for the pin holders 22 and a plurality of recesses 67 for the lugs 23 and intermediate body of metal 68. In addition, the mold section 47 is 25 provided with a plurality of tongues 65, which fit in grooves 64 in the mold section 46 in such relation as to insure the parts always fitting in the same relation to each other.

It will be understood that before the metal is 30 poured a ring of inserts, as shown in Figure 12, and having the pin holders 22 assembled in position, is placed in the mold as indicated in Figures 2 and 3. To assist in holding this ring of 35 inserts in position before casting, and to assist also in removing the ring of brake shoes from the mold, a holding arrangement is provided.

Referring more particularly to Figures 5 and 7 to 10, the mold sections 46 and 47 are provided with aligned recesses 74 and 73 in which L-shaped 40 hooks 72 are provided. The end of hook 72 is adapted to pass through the holes 28 of the pin holder 22, as shown best in Figure 10. The hooks 72 are secured to a ring 71 and are supported on guides 69, which are secured to the mold section 47. The ring 71 is further supported in guides 70 between the arms 63 and the mold section 47.

The coil spring 75 is provided to normally hold the hooks 72 out of engagement with the brake shoe pin holder 22. A notch 77 is provided in 50 the ring 71, and a latch 76 engages the notch 77 to hold the hooks 72 in the holes 28 of the brake shoe pin holder. When the latch 76 is tripped, it will be understood that the spring 75 pulls the hooks 72 out of the pin holders.

If desired, a pin 78 may be secured to the ring 71 and cam 79 operated by suitable means, such as a solenoid may be provided for engaging the pin 78 to move the ring 71 to allow latch 76 to engage in notch 77.

For pouring the cast iron a pouring arrangement 82 for each unit is provided. The pouring arrangement comprises a ladle 80 pivoted by pivot 81 on a support 82, which is carried by carriage 48. A pair of rollers 84 and 86 are supported by the pedestal 82, and a line 85 passes over these rollers. The line 85 is fastened at one end into a lug 83 secured to the ladle 80, and at the other end it passes around a drum 87 which is driven by a motor 88, both of which are 65 mounted on the carriage 48. Thus it will be seen by driving motor 88 the ladle 80 may be lifted about its pivot 81, and the contents poured into trough 90.

To carry the molten metal into the mold a 70 trough 90, a water-cooled pipe 91 and a spout 92

are provided. The water-cooled pipe 91 is carried by a roller bearing 97 and by a support 98. The trough 90 may be clay lined, as indicated by 89 in Figure 16.

The water-cooled pipe 91 is made up of an 5 inner tube 93 and an outer jacket 94 with a partition 202 extending therebetween, so that cooling water introduced through pipe 95 must flow the length of the pipe 91 before it can flow out through pipe 96.

10

One of the arms 63 may have a recess which is adapted to be engaged by a projection 203, which may be operated by a solenoid or in any other manner to hold the casting machine in a pre-determined position when desired. A suitable 15 chain 204 supported by a suitable overhead carrying arrangement (not shown), and a second chain 205 also form part of the apparatus for carrying out the invention.

Thus, apparatus has been described which 20 comprises two complete casting machine units, which are to run by the same motor 30. It will be understood that these units are identical in construction, and that the operation thereof is 25 identical and they are adapted to be operated simultaneously.

To carry out the process of making a brake shoe according to the invention and utilizing the apparatus above described, a ring of material, as indicated in Figure 12, is formed of sufficient 30 length to fit within the molding machine. This material may be of steel and the ends of the ring may be arranged to come at a point between the finished brake shoes. The pin holders 22 are put in position with their projections 27 fitting in 35 the slots 26 and bent thereunder, and the composite insert is placed in the mold with the pin holders in the recesses 66. If convenient, the insert assembly may be placed in the mold after it is closed, as shown in Figure 2, or it may be 40 placed in the mold with the mold in open position, as indicated in Figure 6. If the latter procedure is desirable, the mold is closed by moving the carriage 48. The cam 79 is then operated to rotate ring 71 which causes the hooks 72 to 45 engage in the pin holders 22 of opposite shoes of the ring of brake shoes, as indicated particularly in Figure 3. This causes the latch 76 to drop in the notch 77 to hold the hooks 72 in position.

The motor 30 is started and the centrifugal 50 mold is driven up to suitable speed for centrifugal casting. The exact amount of molten iron is placed in the ladle 80 by a suitable bucket or other mechanism (not shown) for casting a ring of brake shoes. It will be understood that sufficient iron must be placed in the ladle 80 to form a ring of brake shoes whose inside diameter is substantially equal to the diameter of the wheel that it is to work with.

When the main motor 30 has gotten the centrifugal molds up to speed, the ladle tilting motor 88 is started, and the ladle 80 is tipped pouring the molten metal into the trough 90 whence it flows through pipe 91 and spout 92 into the annular mold space. It will be understood that 65 spout 92 is so arranged and is disposed in such position and direction to fill the mold space while the mold is rotating with a minimum of splashing of the molten iron.

The molds are rotated until the iron is set at 70 which time the motor 30 is stopped with the molds in such position to allow the pin 203 to be inserted in its recess in the arm 63. The ring of brake shoes is preferably removed from the mold 75

while still at a bright yellow heat to increase the life of the mold. The carriage motor 55 is then started and the carriage moves to the position shown in Figure 6. The hooks 72 being engaged with the ring of brake shoes assist in pulling the entire ring of brake shoes with the movable mold section 47. While in the position shown in Figure 6, the chain 205 is engaged with the pin holder of an adjacent brake shoe of the ring of brake shoes, and the chain 204 is engaged with the pin holder of an opposite brake shoe of the ring of brake shoes. If necessary the carriage

probably be found suitable for the permanent mold parts, and the practice of removing the castings from the machine as soon as possible after they are set, thereby keeping the machine at as near a uniform temperature as possible, will be found to be advantageous in increasing the life of the mold. 5

While certain novel features of the invention have been shown and described and are pointed out in the annexed claims, it will be understood that various omissions, substitutions and changes may be made by those skilled in the art without departing from the spirit of the invention. 10

- for a plurality of circularly arranged brake shoes, means for separating said parts axially, holding members mounted on one of said parts for engaging in recesses in the plurality of brake shoes
- 5 for fixing said brake shoes in said part, and means for introducing molten metal into the mold space.
6. In apparatus for casting a device centrifugally, an annular mold having an axially fixed
- 10 section and an axially movable section, means for readily separating said sections, means for rotating said mold, holding means on said axially movable section to carry the device with that mold section when the sections are separated,
- 15 and means for anchoring said device to a rela-

tively fixed point, whereby further axial movement of said axially movable section will remove said device therefrom.

7. In apparatus for casting a product centrifugally, an annular mold comprising axially stationary and axially movable sections, means for rotating said mold, a carriage, means for moving said carriage axially of the axially stationary section, said axially movable section having a hollow hub journaled on said carriage, a feed conduit 10 within said hub communicating with the mold space, and means for supplying said conduit with molten metal.

CARRIE J. WEAVER,
Executrix of William B. Weaver, Deceased. 15
